UNITED STATES PATENT OFFICE.

JOHN J. HEYS, OF LYNN, MASSACHUSETTS, ASSIGNOR OF ONE-HALF TO
MAURICE V. BRESNAHAN, OF LYNN, MASSACHUSETTS.

SOLE-MOLDING MACHINE.

No. 810,940.

Specification of Letters Patent.

Patented Jan. 30, 1906.

Application filed November 26, 1902. Serial No. 182,843.

To all whom it may concern:

Be it known that I, JOHN J. HEYS, of Lynn, in the county of Essex, and State of Massachusetts, have invented certain new and useful Improvements in Sole-Molding Machines, of which the following is a specification.

This invention has relation to presses, and more particularly that class of presses which is employed in the molding or shaping of soles for boots and shoes.

In order that a sole may properly conform to the last and to the foot of the wearer, it is necessary to mold or press it into shape, and this is accomplished by means of two complementary members commonly termed "male" and "female" molds. These molds are mounted in a press in such manner that the sole may be placed between them when they are separated, after which they are brought together to press or shape it. Heretofore it has been customary in machines of this character for the operative to place each sole by hand between the molds, putting it in such location as his experience or judgment might dictate, and consequently it has rarely been the case that two soles have been molded exactly alike except by accident. The molding of the sole serves to bend that portion of the sole which lies below the ball of the foot in a curve in the direction of its length, as well as transversely, to form between the front portion and the shank a sharp break or "bend," as it is termed, and to curve the shank itself longitudinally of its length as well as transversely, the longitudinal curvature of the shank, however, being opposite to the curvature of that portion of the sole which is below the ball of the foot. These lines or curvatures vary with the different styles and sizes of boots and shoes; but it is essential that under all conditions the break or sharp bend should be located at a particular line with reference to the toe of the sole in order that the curvature of the shank portion shall bear the proper relation to the upper of the shoe or the last upon which it is to be laid. By properly locating the bend or break with relation to the toe, in the first instance, it is possible to so form or mold the shank portion of the sole that it will lie snugly against the shank of the last and permit the upper to be drawn taut across the waist of the shoe, so that the shank portion of the sole and the waist of the upper will properly support the arch of the

foot. Inasmuch as the majority of shoes are improperly molded by promiscuous location of the bend or break with reference to the toe, it will be at once apparent that in the operation of securing the sole to the lasted shoe the relatively light upper and insole are caused to conform to the lines of the relatively heavy sole, and consequently the shoe is rendered misshapen and is unable to support the arch of the foot. It is for this reason that many persons who are compelled to stand suffer from a broken-down metatarsal arch and the pain and discomfort attendant thereupon.

According to the present invention I provide means for accurately locating the molds and for automatically introducing each sole between the complementary molds and positioning it properly between them, so that the molds will act with accuracy upon the sole in every instance according to its size. In addition the molded sole is returned automatically to the operator when the molds are separated. To provide for this returning of the sole, I reverse the arrangement of the molds that has hitherto been followed by securing the female die to the stationary cross-head and secure the male mold to the movable table or support. The molds move toward and from each other vertically, and the sole is fed at an angle to the direction of their movement. In addition to thus providing for the accurate molding of the sole the mechanism for feeding the sole renders the machine automatic and obviates the necessity of the operative placing his hand in a dangerous position with relation to the molds. In addition to the features thus referred to, the mechanism which I have provided is equipped with gaging mechanism, whereby the same feeding devices may be employed for all styles and sizes of molds and soles molded thereby from the smallest infants' sizes to the largest men's sizes. By means of this gage the operator is enabled to quickly adapt the feeding mechanism for various sizes and styles of soles.

On the accompanying drawings, which illustrate a portion of a molding-machine equipped with one embodiment of the present invention, Figure 1 represents a horizontal section through the same. Fig. 2 represents a section on the line 2-2 of Fig. 1. Fig. 3 represents a front elevation of one of the feeding devices. Figs. 4 and 5 represent the

sole-clamping members in different positions. Figs. 6, 7, and 8 represent male molds of different sizes and lengths and illustrate how they are secured to the table or support in 5 the same relation to the feeding-fingers. Fig. 9 represents the scale-plate.

The invention is illustrated as applied to a machine of the general character of that illustrated in Letters Patent No. 607,370, granted 10 to me July 12, 1898; but it will be understood that it is not limited in its application and that it may be made in various ways without departing from the spirit and scope of the invention. It will be understood, further, that 15 the phraseology which I have hereinafter employed is for the purpose of description and not of limitation.

On the drawings the machine is illustrated as provided with the side standards 10 10 and 20 the uprights 11 11 11, to which is secured the cross-head 12 and which provide guides for the movable tables or supports 13. The said supports are moved vertically toward and from the cross-head by any suitable means 25 and are preferably operated alternately or independently, as occasion requires. To the cross-head and the tables 13 are attached the female and male molds 15 16, respectively. Each male mold rests upon a wedge 17, which 30 will be adjusted as specified in my said Letters Patent No. 607,370. Projecting upwardly through the said wedge are two index or locating pins 19 19, which serve the function of properly positioning the male molds 35 and holding them against longitudinal or transverse movement, said molds being provided with apertures to receive said pins, as indicated, as will be hereinafter explained in greater detail.

40 The feeding mechanism for holding the soles between the molds are located upon the tables 13, each mechanism comprising members or fingers for grasping the soles and carrying them into position between the molds and for returning said soles after they have 45 been molded. In addition each feeding mechanism is capable of adjustment so as to lay the sole properly with relation to the molds, so that the same mechanism may be 50 used in connection with all sizes and shapes of soles for the shoes of men, women, and children. As the two feeding mechanisms for the two sets of molds are similar, only one of them need be described.

55 The support or table 13 for the male die is provided with two brackets 22 23, respectively, attached to the rear and front ends thereof.

60 24 indicates a bar movable longitudinally of the length of the molds and arranged at one side thereof. Said bar 24 is mounted in guides 25 26, respectively. The guide 25 is adjustably secured to a laterally-extending pin 27, which is pivoted by a screw 28 to an 65 upright pin 29, adjustably arranged in a

socket in the bracket 22. Clamping-screws 31 32 respectively serve to adjustably secure the guide 25 to the pin 27 and the pin 29 to the bracket 22, so that said guide has a universal adjustment. The guide 26 for the front end of the bar 24 is adjustably secured to a laterally-extending pin 33, pivoted by a bolt 34 to an upright pin 35, adjustably secured in the upper end of the bracket 23. The bolts or pintles 34 28 may be screwed home to hold the pins 27 33 either in horizontal or in inclined position. According to this method of adjustment of the bar 24 it may be arranged in exact relation to the molds, so that it may be located upon any type of sole-molding machine. The bar 24 carries and actuates the sole-feeding mechanism. The means for reciprocating the bar 24 includes a segmental rack 40, formed on an arm 41, which is pivoted upon a stud 42, projecting laterally from the bracket 22. Formed with the arm 41 is a second arm 43, having a roll 44 extending into a cam-path 45, formed in a bracket 46. This bracket is supported upon the frame. Its lower end is formed with an 46 aperture 461, vertically elongated to receive a cross-bar 47, extending between the standards 10 10 of the machine. Adjustable oppositely-projecting set-screws 48 48 are passed into the aperture 461, so as to adjustably support the bracket upon the rod or cross-bar 47. The upper end of the bracket is adjustably clamped to the side standard 10 of the machine by any suitable means, as by a clamp 49 on the outside of the standard and the screw 50 passed therethrough into the bracket 46. The cross-bar at 47 is one of the tie-rods of the machine and is relied upon to hold the bracket against movement, being connected to the bracket by the oppositely-projecting set-screws 48. The provision of the set-screws enables the adjustment of the bracket. The said cross-bar is mounted in the side standards 10 10 of the machine. The bar 24 is provided with rack-teeth 51, intermeshing with the segmental rack 40. The cam-path 45 has the two vertical end portions *a* and *b* connected by an inclined portion *c*, so that as the table 13 is raised and lowered the arm 43 is caused by the location of its roller 44 in the cam-path to be oscillated about the stud 42, so as to rock the segment 40 and reciprocate the bar 24. The parts are so timed that before the table reaches the upper extreme of its movement the bar 24 is moved to the rear, as shown in Fig. 2, and when the table is lowered the bar is moved forward, and consequently by locating the feeding mechanism upon the bar said mechanism operates to lay the sole between the molds or dies prior to their engagement as the table moves upward and to withdraw the sole from the molds as the table is moving downward.

Adjustably secured to the bar 24, by screws

601, is a carrier 60, upon which are secured the fingers, clamps, or members for engaging the sole and a gage for properly placing or locating the sole with reference to the molds or dies. The fingers or clamps are arranged to engage the edges of the sole near the heel end thereof at the instant that the table 13 begins its upward movement to bring the male die or mold to a position of pressure. The said fingers are indicated at 61, 61, respectively, each being pivoted upon a pin or stud 611. They are connected together by a helical spring 62, which tends to draw their operative pointed ends together, so as to engage a sole laid between them. The ends of the fingers are elongated from top-to bottom and are preferably sharp or knife-edges, so as to indent the leather and secure a firm grip on the sole, and each has a projection 67 to take over the face of the sole. Each finger or clamp is provided with a lateral toothed segment 63, said segments intermeshing, as shown in Figs. 4 and 5, so that the movement of the fingers toward and from each other is simultaneous and to the same extent.

An adjusting-screw 64 is passed through a projection 65 on the guide 26 with its end in position to engage one of the segments 63 as the carrier 60 and the bar 24 reach the end of their retractive movement or as they reach the end of their movement away from the molds. Consequently when the carrier is reaching the extreme of its outward movement the end of the screw 64, being stationary, is struck by one of the segments 63 and the fingers are opened against the tension of the spring 62, so as to release the sole. By providing for the adjustment of the "stop," as the screw 64 may be termed, the fingers 60 may be opened much or little, as occasion requires.

In operation, assuming that the molds are separated and that the table 13 is at the lower end of its movement, a sole may be placed between the fingers with its front portion resting upon the top of the mold 16. Then as the table 13 rises the roll 44 immediately enters the inclined portion c of the cam-path 45 and the rod 24 and the carrier start rearwardly. As soon as the segment 63 leaves the stop 64 the fingers close upon the sole and carry it rearwardly with relation to the molds, so as to place it in proper position between them. After the molds have molded the sole the table 13 moves downward and the carrier 60 is returned to forward position, the fingers 61 opening when the stop 64 is engaged by one of the segments 63. It is desirable and essential, however, that the sole should be placed in exact position with relation to the mold, and therefore there is provided an adjustable gage against which the heel end of the sole may be placed and by which said heel end of the sole may be supported prior to the movement of the sole to

position between the molds. The said gage consists of a rod or bar 70, arranged in parallelism with the rod 24 and placed in a guide-way or aperture in the laterally-extending portion 68 of the carrier 60. The front or inner end of the rod is provided with a horizontal flat web 71 and with two divergent walls or shoulders 72, 72. These walls form an angle of about one hundred degrees, and they are adapted to receive the curved heel end of a sole of any size or width. The sole is placed with its heel end resting upon the web 71 and with its rear or heel edge against the walls or shoulders 72, 72. Consequently when the carrier moves rearwardly the gage 70 pushes the sole forward until the sole is engaged by the fingers 61. The divergent formation of the shoulders or walls 72 permits the accurate centering of the sole and its correct positioning with relation to the fingers 61, 61, and when the sole is engaged by the fingers it is held from lateral movement by its engagement with the gage. The gage is located above the segments 63, as shown in Figs. 1 and 3, but the operative ends of the 80 fingers are vertically extended to bring their knife-edges into position to engage the edge. The lug 67, with which each finger is provided, prevents the sole from being forced out of the fingers by the initial engagement of the molds 95 and before said molds reach their position of pressure. The gage is longitudinally adjustable, so that it may be employed with all sizes and shapes of molds and soles to be molded thereby. For adjusting the gage the rod or 100 bar 70 is provided with rack-teeth 80, with which are engaged the segmental rack-teeth 81, formed on an arm 82, fulcrumed on a stud 83, said stud being secured in the carrier 60. The said arm is provided with an upwardly-projecting boss 84, which forms a handle by 105 means of which it may be swung about the pivot 83, so as to move the gage longitudinally in one direction or the other. The said arm is employed in conjunction with a scale 110 or indicator plate 90. This plate is mounted upon the stud 83, and it is provided with a curved slot 91, through which the boss or handle 84 passes, as shown in Fig. 1. The arm 82 has an index or pointer 86, which may be moved to register with any one of a series of graduations marked upon the plate 90 and which indicate successive sizes of the soles, after which the arm 82 will be secured in position. To this end at each one of the graduations 115 on the plate there is an aperture 92, adapted to receive a locking-pin 93, formed on a lug 94, projecting from a depressible headed pin 95, placed in a socket in the end of the arm 82. A spring (shown in dotted lines at 96 in Fig. 3) 120 holds the depressible pin normally raised, with the locking-pin 93 in one of the apertures 92, and the arm 82 is therefore locked against movement with relation to the indicator-plate 90. By depressing the pin 95 125 130

the arm 92 may be swung in one direction or the other until the pin 93 registers with another hole in the plate 90 for the purpose of adjusting the gage to fit any particular size 5 of the sole. Between the holes 92 there are recesses formed in the under face of the plate 90, into which the pin 93 may be allowed to enter to adjust the gage for half sizes of soles, each hole or graduation representing a full size 10 of the sole. From this it will be observed that with a single pair of molds a plurality of sizes of soles may be properly molded by adjusting the gage with reference to the said molds. The movement of the carrier is always 15 of the same length; but as the sole varies in length it is necessary to adjust the gage toward the mold in molding a small-sized sole and to move the gage away from the mold in molding a large-sized sole in order 20 that the sole may be properly molded to locate the bend or break accurately with reference to the ball-line of the sole. The term "ball-line" is used in the sense in which it is commonly employed in shoe factories as the line 25 which defines the rounding shank from the flat fore part of the shoe. This is the true ball-line, and it is always in the same relative location in all shoes, though the sole is many times improperly molded, so as to 30 locate the bend or break away from the true location of the ball-line. According to the present invention the bend or break is formed in the sole, so as to coincide with the ball-line.

35 It is obvious that while the indicator with its graduations to represent sizes may accurately locate a sole to fit a certain style of shoe or last—as, for instance, for men's shoes—yet it is highly desirable to make provision 40 for employing the same indicator-plate for molding soles for various other styles of men's shoes and also of women's, youths', boys', misses', and children's shoes.

The plate 90 is shown in Fig. 9. The apertures 45 are indicated by symbols, preferably numerals, indicating the sizes of shoes. Boys' and women's shoes are numbered successively from 1 to 8, with half sizes, of course, and the eight apertures 92 are therefore 50 numbered "1" to "8." Said series of numerals are indicated by the letters "B & W," meaning "boys' and women's." Children's and men's shoes are numbered in sizes from 5 to 11, and the apertures 92 (except the 55 first one) are numbered by a second series of numerals "5" to "11," as by the letters "C & M," meaning "children's and men's." Misses' and youths' shoes are in sizes from 11 to 2, and the first five apertures are numbered 60 by a third series of numerals "11 12 13 1 2," as indicated by the letters "M & Y," meaning "misses' and youths'." The molds for shoes are divided into five main lengths—men's, women's, youths', misses', and chil-

dren's—and according to my invention the 65 molds are so located in the machine that the feeding mechanism will properly place the soles between them irrespective of their lengths.

The pins 19 19 are arbitrarily located in 70 the table; but the location of the holes in the male molds is determined by the length of the mold and the relation of the heel end of the mold to the forward extremity of movement of the feeding-fingers. The fingers 75 travel in a fixed path, and therefore when they are in their inward extreme of movement the molds should be so located that the break or bend in the soles will bear the proper relation to the ball-line thereof. As 80 said, a single pair of molds will mold all the sizes of a line of shoes—as, for instance, men's shoes—but the gage is shifted in accordance with the sizes of the soles of that particular line or style. Now the men's 85 molds will be the longest, and the apertures 110 for the pins 19 will be located so that the heel end of the mold will be in position for the fingers to lay the sole between them. (See Fig. 6.) The next shorter molds may be 90 women's, for instance. In this case the apertures 110 will be relatively nearer the toe end of the molds, and the heel end of the molds will occupy the same position that the heel end of the men's molds occupied. The 95 ball-line (indicated at x) is moved nearer the fingers. The next shorter molds, as for youths', will have the apertures 110 still nearer the toe end, and the ball-line x will be again moved toward the finger, and so on, all 100 the molds having their heel ends located in exactly the same place, but the ball-lines being nearer to or farther from the fingers, according to the length of the mold. It will thus be seen that when an operator places a 105 mold in the machine it is accurately located without care on his part and that by moving the arm 82 along the slot 91 the gage may be adjusted to properly position the shoes of different sizes. If the operator is working on 110 men's or children's soles, he is guided by the middle series of numerals, if on boy's or women's he is guided by the first or inner series of numerals, and if on misses' or youths' he is guided by the third or outer series of numerals 115 on the plate 90, adjacent the apertures 92; but the shoes of each class vary greatly according to style, and the molds for men's shoes, for instance, may be made for many different styles. Therefore said plate 90 is 120 loosely pivoted upon the stud 83 and is formed with a curved slot 100, through which the shank of a thumb-screw 101 is passed into a boss 102 on the carrier 68. The plate, with the arm 84, may be swung about 125 the stud 83 and secured in any desirable position by the thumb. The operator in working upon men's soles—a style 47^x, for example—

sets the arm 82 to 5 "C & M" and adjusts the plate 90 until the sole which is grasped by the fingers is accurately located between the molds. The thumb-screw is screwed tight, after which the arm 82 may be swung along the scale for the various sizes of soles. The operator may with a sharp instrument mark a line on the face of the plate outside of the slot 100 to register with the thumb-screw and indicate it by a symbol, as 47^X, and then whenever it is necessary to mold soles on 47^X molds the plate may be quickly adjusted to bring the line in registration with the thumb-screw.

15 It is unnecessary to specifically enumerate the advantages of this invention more than has been done, for they will be apparent to those skilled in the art to which this invention relates.

20 Having thus explained the nature of the invention and described a way of constructing and using the same, although without attempting to set forth all of the forms in which it may be made or all of the modes of 25 its use, I declare that what I claim is—

1. In a sole - molding machine, complementary molds and mechanism movable bodily with relation to the molds and supported independently of said molds for automatically grasping a sole, feeding it to a position 30 between the molds, holding it between the molds during the molding operation, and withdrawing it therefrom after it is molded.

2. In a sole - molding machine, molding mechanism, devices for grasping a sole, and automatic mechanism for actuating said devices relatively to said molding mechanism in consequence of which they feed a sole to the molding mechanism, hold it during the 40 molding operation, and withdraw it from the molding mechanism.

3. In a sole - molding machine, molding mechanism, a reciprocating sole-grasping device, means for reciprocating said device to cause it to place a sole in the molding mechanism and to withdraw it therefrom, and means for causing said device to grasp and release the sole.

4. In a sole - molding machine, molding mechanism including molds movable toward and from each other, a sole-engaging device, means for causing said device to grasp and hold a sole, and means for moving said device transversely with relation to both of said 55 molds, to feed the sole between the molds and there hold it without said device lying between the molds.

5. In a sole - molding machine, molding mechanism including complementary molds 60 movable toward and from each other, a sole-engaging device, means for causing said device to grasp the heel end of a sole, and automatic mechanism for moving said device relatively to said molds to feed the sole between the molds to hold it there during the molding

operation and to withdraw it therefrom after it is molded.

6. In a sole - molding machine, molding mechanism, a reciprocating carrier movable toward and from the molding mechanism, a 70 guide therefor, coacting fingers mounted on said carrier and adapted to engage the edges of a sole, means for opening and closing said fingers when said carrier is remote from the molding mechanism, and means for actuating 75 said carrier.

7. In a sole - molding machine, molding mechanism, fingers adapted to engage the side edges of a sole at the heel end thereof, a carrier movable in lines substantially parallel to the longitudinal lines of the molds, and means for actuating said carrier and said fingers whereby said fingers carry a sole between the molds and hold it until the molds compress the sole. 80

8. In a sole - molding machine, molding mechanism having coacting molds movable toward and from each other, coacting fingers adapted to grasp a sole between them, means for moving said fingers relatively to said 90 molds in lines longitudinal of the sole grasped thereby to feed the sole longitudinally between the molds, and means for causing said fingers to release said sole only when said fingers are remote from said molds.

9. In a machine for molding soles, molding mechanism comprising molds which lack a portion of the heel end whereby the heel of a sole placed between them will project beyond the heel ends of the molds, and automatic 100 means independent of the molds and movable toward and from them for grasping the heel end of a sole and inserting it between the molds, whereby said means may continue to grasp the sole while it is initially engaged by 105 the said molds, and thus prevent the dislocation of the sole.

10. In a sole - molding machine, molding mechanism including complementary molds 110 movable toward and from each other, fingers adapted to engage the side edges of a sole at or near its heel, and mechanism for actuating said fingers to place a sole between the molds.

11. In a sole - molding machine, molding mechanism including complementary molds 115 movable toward and from each other, a carrier, means for moving said carrier relatively to said molds in lines transverse to the lines of movement thereof, and sole - grasping means mounted on said carrier, and adapted 120 to hold the sole against dislocation without said means lying between said molds.

12. In a sole - molding machine, molding mechanism including complementary molds 125 movable toward and from each other, a pair of coacting fingers adapted to engage a sole between them, mechanism for moving said fingers to place a sole engaged thereby between the molds, and mechanism for automatically opening and closing said fingers, 130

said last-mentioned mechanism causing said fingers to remain closed on the sole during the molding operation.

13. In a sole - molding machine, a pair of 5 molds of which one is movable, a movable support for the movable mold, and automatic sole - feeding mechanism mounted on said movable support and comprising a sole - grasping device, and means for bodily moving said device relatively to the movable mold in lines transverse to the lines of movement of the mold-support whereby said device places a sole between the molds and then withdraws it therefrom, without said device 10 lying between said molds.

14. In a sole - molding machine, a pair of molds, a movable support for one of said molds, adapted to move from a position of clearance to a position of pressure and vice 20 versa, a sole-grasping device movable transversely of the path of movement of said support, and automatic mechanism for moving said device from a sole-receiving position to a position in which the sole carried thereby is 25 located between the molds, without said device entering the space between the molds, said mechanism being timed whereby the sole is placed between the molds, when said support is in a position of clearance.

15. In a sole - molding machine, molding mechanism, coacting fingers for grasping a sole, a carrier for said fingers movable relatively to the molding mechanism, means for causing said fingers to close, means for actuating said carrier to cause the fingers to feed and hold the sole between the molds, and means for opening the fingers after they have withdrawn the sole from the molds.

16. In a sole - molding machine, a sole - feeding mechanism comprising a device for supporting the heel end of the sole, means for engaging the side edges of said sole, and provisions for moving said device and said means in a direction longitudinally of the sole.

17. In a sole - molding machine, coacting molds, means for feeding a sole between said molds comprising fingers for gripping the sole between them, and means for moving said fingers relatively to the said molds to feed 50 the sole between them, and a gage adjustable with relation to said fingers to determine the points where the sole is gripped by the fingers.

18. In a sole - molding machine, molding mechanism, sole - feeding mechanism comprising a reciprocating carrier adapted to move toward and from the molds, a pair of connected fingers mounted on said carrier, a spring for closing said fingers, and means for opening said fingers only when the fingers are 60 remote from said molds.

19. A sole - feeding attachment for a molding - machine comprising supports, a reciprocating carrier thereon, mechanism for reciprocating the carrier, a gage on said carrier, 65 coacting fingers adapted to grasp the heel

end of a sole and to coact with the gage in feeding the sole from a point remote from both molds to a position between the molds, and means for causing the opening of said fingers only when they are remote from the 70 molds.

20. A sole - feeding attachment for a molding - machine comprising movable supports, a carrier adapted to reciprocate thereon and having rack-teeth, a toothed segment meshing with said rack-teeth and having an arm, a path-cam attached to the frame of the machine and engaged by said arm, and a sole - engaging device on said carrier. 75

21. The combination, with a molding - machine having complementary molds, of a sole - feeding mechanism comprising devices for engaging and feeding a sole a predetermined distance relatively to both of said molds and a gage movable with relation to said devices 80 in lines longitudinal of the lines of movement of the said devices, to position the sole relatively to said devices.

22. The combination, with a molding - machine having complementary molds, of a sole - feeding mechanism comprising a carrier movable relatively to both of the molds, means for so moving said carrier, means on said carrier for engaging and feeding a sole between the molds, and an adjustable gage on said carrier 90 movable relatively to said engaging means for determining the extent of movement of the sole between the molds. 95

23. The combination, with a molding - machine having complementary molds, of a sole - feeding mechanism comprising a reciprocating carrier movable with relation to said molds and having coacting fingers for engaging the sole and feeding it between the molds, and a gage on said carrier for engaging the heel end of the sole and determining the extent of movement of the sole. 100 105

24. A sole - feeding mechanism for molding - machines comprising coacting fingers for engaging the side edges of the sole, a carrier for said fingers movable longitudinally of the sole, a gage on said carrier for engaging the heel end of the sole, and means whereby said gage may be adjusted longitudinally of the lines of movement of the carrier. 110 115

25. An attachment for molding - machines comprising devices for engaging and feeding a sole between the molds, means for moving said devices relatively to the molds, and a gage movable relatively to said molds and with said devices, said gage having a portion to project under the heel end of the sole, and two angularly-disposed faces to engage the sole at the heel end. 120

26. The combination, with a molding - machine having complementary molds, of a sole - feeding mechanism comprising devices for engaging a sole and feeding it relatively to the molds, and a gage having a portion to project under the heel end of the sole, and a 125 130

portion to engage the edge of the sole at the heel end, means for moving said devices and said gage longitudinally of the sole to feed the same between the molds, and means whereby said gage may be adjusted relatively to said devices.

27. The combination with a molding-machine having complemental molds, of a sole-feeding mechanism comprising sole-engaging devices, means for moving said devices relatively to the molds to feed a sole between the molds, an adjustable gage for positioning the sole relatively to said sole-engaging devices, and an indicator for showing the position of the gage.

28. The combination, with a molding-machine having complemental molds, of a sole-feeding mechanism comprising sole engaging and feeding devices for engaging a sole and feeding it relatively to the molds, an adjustable gage for the sole for positioning the sole relatively to said device, an index connected to the gage, and a scale in operative relation to the index.

29. A sole-feeding mechanism for molding-machines comprising sole-engaging devices, an adjustable gage for the sole, an index connected to the gage, and a scale in operative relation to the index, said scale having gradations with a plurality of symbols indicating the several sizes of shoes of different character.

30. In a molding-machine, the combination with complemental molds of sole-feeding devices movable bodily relatively to the molds to feed a sole therebetween, a movable gage movable with the sole-feeding devices, a handle for adjusting said gage with relation to said devices, and means on the handle for securing said handle and thereby said gage in any one of a plurality of positions.

31. A sole-feeding mechanism for molding-machines comprising a movable gage, an index connected to said gage, an adjustable scale having graduated provisions for the attachment of the index, and means for securing the scale-plate after adjustment.

32. A moldir-machine comprising molds

and mold-supports, sole-feeding devices movable relatively to the molds, a gage, and means for moving said devices and said gage, said gage being adjustable relatively to the said devices in accordance with the size of the sole to be molded, to position the sole relatively to said devices.

55

33. A sole-molding machine comprising molding mechanism, sole-feeding devices, a gage, means for adjusting said gage relatively to said devices for soles of different kinds, provisions for adjusting said gage relatively to said first-mentioned means for different sizes of soles of the same kind, and means for actuating said devices and said gage relatively to said molding mechanism.

34. A sole-molding machine comprising molding mechanism, automatic sole-feeding devices independent of and movable relatively to said molding mechanism, and having a uniform range of movement, and a sole-gage movable with said devices but adjustable relatively thereto.

35. A sole-molding machine comprising complemental molds, and automatic sole-feeding mechanism movable with relation to the molds and having provisions whereby soles of different lengths may be laid by said sole-feeding mechanism between the said molds with the ball-line of each sole registering with the ball-line of the molds.

36. A series of pairs of complemental molds of different lengths, one mold of each pair having a device by which it may be secured to its support, the devices on all of the said molds so provided being at the same distance from the heel ends.

85

37. A series of pairs of complemental molds, of different lengths, one mold of each pair having a pin-receiving aperture, and the said apertures in all the molds being at the same distance from the heel ends.

90

In testimony whereof I have affixed my signature in presence of two witnesses.

JOHN J. HEYS.
